COMPRESSOR

Walter R. Freeman, Clayton, Mo., assignor to
Wagner Electric Corporation, St. Louis, Mo., a
corporation of Delaware

Application May 21, 1943, Serial No. 487,863

9 Claims. (Cl. 230—24)

My invention relates to compressors and more particularly to rotary compressors of the type provided with a stationary stator and an eccentrically mounted rotor provided with blades.

One of the objects of my invention is to so construct a rotary compressor that it will be compact, easy to manufacture, assemble and repair, and one which will also be efficient in operation.

Another object of my invention is to produce a rotary compressor construction in which the unloading valve mechanism is incorporated in the stator body member.

Yet another object of my invention is to provide improved means for mounting and driving the rotor of a rotary compressor.

A still further object of my invention is to so construct a rotary compressor that external piping will not be required for the various conduits associated with the stator, the rotor, the unloading valve mechanism, the oil reservoir, and the separator.

Other objects of my invention will become apparent from the following description taken in connection with the accompanying drawings in which Figure 1 is a top view of a rotary compressor embodying my invention; Figure 2 is a sectional view of the compressor taken on the line 2—2 of Figure 1; Figure 3 is a sectional view taken on the line 3—3 of Figure 2; Figure 4 is a sectional view taken on the line 4—4 of Figure 2 and showing details of one end plate; Figures 5 and 6 are sectional views taken on lines 5—5 and 6—6, respectively, of Figure 1 and showing various passages; and Figure 7 is a partial sectional view showing the oil separator construction.

Referring to the drawings in detail, numeral 1 indicates a stator body member having a cylindrical opening 2, the ends of which are closed by end plate members 3 and 4 bolted to the stator. The end plate member 3 is formed with an extension 5 in which is provided a shaft receiving bore 6, the remaining portion being hollow to provide an oil reservoir 7.

Received and supported in bore 6 is a rotor shaft 8 having a portion 9 extending into opening 2 of the stator with its axis eccentric to the axis of said stator opening. The portion of the shaft positioned in bore 6 is hollow to form a chamber 10. The open end of extension 5 on the end plate is provided with a cover plate 11 held on the extension by bolts 12. This cover is provided with an opening 13 in axial alignment with the shaft receiving bore 6 and extending into this opening is a threaded portion of a nut 14 for cooperation with internal threads on the end of

shaft 8. The nut is employed to close the hollow end of the shaft and to also draw the shoulder on the integral flange 15 of the rotor shaft against the inner surface of the end plate member 3 to thus secure the shaft against any rotation in the end plate member.

The portion 9 of the shaft which projects into the opening of the stator member has rotatably mounted thereon a rotor 16 provided with a cylindrical surface 17. This rotor is provided with four slots 18 in which are slidably mounted blades 19 as in well-known constructions.

The rotor and blades are adapted to be driven by a driving shaft 20 mounted in the end plate member 4 and axially aligned with the rotor shaft 8. The inner end of this driving shaft 20 is of square formation and is received in a square hole in a connecting member 21 forming the bearing for the shaft. The inner end of member 21 is provided with axially projecting teeth 22 which are adapted to be received in slots 23 in the rotor to provide a readily detachable driving connection. The driving shaft may be driven from any suitable source of power and is shown as being provided with a pulley 24.

In order to seal the driving shaft the exterior of the end plate member 4 has bolted thereto a plate 25 which carries a sealing ring 26 made of carbon or like material and interposed between this sealing ring and the plate member is a packing ring 27. The sealing ring is formed with a flat surface 28 which cooperates with a flat surface 29 on the end of member 21. To cause these two flat surfaces 28 and 29 to be held in pressure engagement, the end of the rotor shaft is provided with a bore 30 in which is positioned a spring 31 which acts through a ball 32 against an insert member 33 carried by the connecting member 21.

As will become apparent later, the oil contained in the oil reservoir 7 is under pressure as a result of being acted upon by the pressure developed by the compressor and in order that this oil may be transmitted to the working parts of the compressor to properly lubricate them, the end plate member 3 is provided with a drilled passage 34 which leads from the bottom of the reservoir to an annular groove 35 in the shaft receiving bore 6. This groove communicates with the hollow portion 10 of the shaft through holes 36 and the hollow portion of the shaft is in turn connected by passages 37 and 38 with the exterior of the shaft portion 9 upon which the rotor is mounted. From here the oil can flow along the shaft to the end plates and provide the proper lubrication. In order that the oil may be filtered, the hollow

portion 10 of the shaft has mounted therein an oil filter cartridge 39 in the form of a cylinder and thus oil, in passing from holes 36 to passage 31, must go through the oil filter.

As best shown in Figures 4 and 5, the outlet port 40 of the compressor is positioned in the end plate member 3 and this port communicates with drilled passages 41 and 42 which lead to the inlet passage 43 of an oil separator 44 which is bolted upon the portion of the end plate member 3 above extension 5. This oil separator may be of any desired construction but, as shown in Figure 7, it comprises a body member 45 surrounded by a cup-shaped shell 46. The body member is formed with a plurality of grooves 47 in its surface, which grooves together with shell 46, provide a conduit through which compressed air coming from the outlet port may flow and have its direction changed in order to cause the oil, which is carried by the air in small particles and a mist, to be separated from the air. The top groove of grooves 47 communicates with the inlet passage 43 of the separator so that the air is caused to pass through the various grooves 47 which communicate with each other and form a continuous conduit to the outlet passage 48 of the compressor. This outlet passage is adapted to communicate with the top of the oil reservoir 7 through a passage 49 in the end plate member (see Figure 6). The oil which has been separated by the separator will flow back into the oil reservoir through passages 48 and 49 and the air from which the oil has been separated will pass out of the top of the oil separator through opening 50 (see Figure 2), a passage 51 in the lower part of the separator and through a central chamber 52 in the body member of the separator to a pipe 53 connected to the top of the separator. The pipe can be connected to any suitable receptacle such as a storage tank. Between the chamber 52 and the pipe is a check valve 54 for preventing any return of air from pipe 53 to the oil reservoir or the separator.

The top of the stator member is provided with an integral enlarged portion 55 in which is embodied a stepped bore 56, the axis of which is at right angles to the axis of the opening 2 in the stator member. One end of this bore communicates with the interior of the opening of the stator member by way of a passage 57, the open end of said passage forming the inlet port to the compressor. The other end of the bore communicates with atmosphere by way of a pipe 58 and an air cleaner 59 (see Figure 1). Adjacent this latter end of the bore is a valve seat 60 which has cooperating therewith a valve element 61 carried by a stem member 62. The valve is normally biased to open position by a spring 63 positioned in the bore, said spring abutting against the end of an adjustable member 64 which is threaded in a closure plug 65 of the bore. Thus by adjusting the member 64, the tension of the spring can be varied. This adjustable member also carries a check valve 66 through which the air must flow in coming from the air cleaner to the inlet port, the check valve being employed for preventing a "blow-back" of air from the compressor through the inlet port under certain operating conditions.

The purpose of valve 61 is to cut off the intake of air to the compressor and thus unload the compressor and it is desirable that it be operated when the air pressure developed by the compressor reaches a predetermined value, say, for example, one hundred pounds per square inch. In

order to accomplish this valve closing against the action of spring 63, the valve stem member 62 has associated therewith a diaphragm 67 positioned in a chamber 68 formed by a plate member 69 bolted to the stator member at the end of bore 56. Communicating with chamber 68 is a passage 70 in the body of plate member 69 which has connected thereto a passage 71 drilled in the body of the stator member. Also drilled in the stator member is an angular passage 72 communicating with passage 71, said passage 72 extending to the face of the stator member which cooperates with the end plate member 3 (see Figures 3 and 5). Passage 72 in turn communicates with a drilled passage 73 in the end plate aligned with the end of a passage 74 extending through the body of the oil separator to a point above the check valve 54. Thus it is seen that by passages 70 to 74, chamber 68 is in constant communication with pipe 53 and the storage tank which receives compressed air from the compressor. Thus when this compressed air reaches a predetermined value, it causes diaphragm 67 to move, overcoming the action of spring 63 and causing seating of valve element 61. No more air can enter the compressor. Whenever air is used from the storage tank in a sufficient amount to lower the pressure of the compressed air to such a value that spring 63 can overcome the force acting on the valve stem member by the compressed air, the valve element 61 will again be opened and the compressor allowed to operate to compress additional air.

Whenever the compressor is unloaded, that is, the valve element 61 closed, it is not desirable to have the oil in the oil reservoir under pressure as such forces too great a quantity of oil to the working parts of the compressor where it will accumulate in the chambers and must be forced out before the compressor can begin to efficiently compress air after valve 61 is opened. In order to unload the oil reservoir, that is, connect it to the atmosphere so that air under pressure will no longer be acting on the oil therein, the top of the reservoir opposite the opening 50 has a venting passage 75 (see Figure 2) which aligns with a drilled passage 76 in the enlarged portion 55 of the stator member. This passage 76 in turn communicates with a second drilled passage 77 at right angles and extending to the top of the enlarged portion 55. Positioned on the top of this enlarged portion is a cap member 78 in which is a passage 79 so arranged as to communicate with passage 77 when the cap is in position. The cap carries a cylindrical portion 80 extending into a bore 81 just above bore 56. Bore 81 communicates with bore 56 by means of an opening 82. Bore 81 also communicates with passage 79 in the cap by means of an opening 83 and with a drilled passage 84 by means of an opening 85, the latter passage communicating with the atmosphere through pipe 58 and the air cleaner. The opening 83 is normally closed by valve element 86 which is in the form of a piston slidable in the cylindrical extension. A spring 87 of predetermined strength holds the valve element closed.

When valve element 61 is closed to unload the compressor, the compressor will no longer compress air and the air which is in the compressor will be forced out, thus creating a sub-atmospheric pressure in the compressor. This sub-atmospheric pressure is also present in bore 56 and bore 81 in which the valve element 86 is positioned. This sub-atmospheric pressure to-

gether with the pressure acting on the valve element by way of passages 19, 17, 16, and 15 will cause the valve element to become unseated against the action of spring 81, thus placing the reservoir in communication with the atmosphere. When the oil reservoir is under atmospheric pressure, the rate of flow of oil to the working parts of the compressor will be substantially diminished.

From the foregoing description of my improved compressor, it is seen that a very compact structure has been produced in which there is no piping on the exterior of the structure. All the required passages leading to and from the compressor, the reservoir, the oil separator, and the unloading valve mechanism are formed by drilled holes in various parts. The compressor may be very quickly disassembled if desired. The driving shaft can be removed separately without the necessity of removing the end plate member 4. Also, if it is desired to replace an oil filter, this can be easily accomplished by merely removing one nut. It is also to be particularly noted that in the structure just described only one bearing support is employed for mounting the rotor shaft and that this is in one end plate only. By employing the rotor shaft and rotor mounting shown the rotor will be caused to rotate upon the end portion of the shaft and the only wear which will take place will be uniformly distributed between the shaft and rotor over the surface with which they are in contact. Once the shaft is in position, it will not become cocked when wear takes place and thus result in the rotor scoring the end plates or the stator. Also, due to the construction of the stator and rotor shaft 9 most of the wear on the rotor shaft will occur at the lower side of the shaft due to the fact that the rotor is being pushed upwardly by the compressed air in the compressing compartment near the bottom of the rotor. Due to the lubricating arrangement, oil will always be freely fed to the surface of the rotor shaft and since this will be at the point of greatest wearing pressure, the wear will be minimized.

The arrangement is also such that in assembling the compressor it is not necessary to first assemble, disassemble, and then reassemble in order to get the parts properly aligned, particularly the "close point" between the stator and rotor. The stator can be properly located by merely employing a dowel pin 88 (Figure 2). The hole in the end plate member 3 for receiving the dowel pin 88 can be accurately measured from the axis of bore 6 which receives the rotor shaft. The hole in the stator member which receives the dowel pin can also be accurately determined. Thus during assembly all that need be done to have the end plate properly positioned with respect to the stator to obtain the desired "close point" is to put the dowel pin either in the stator or in the end plate and position the other member to receive the dowel pin. Any slight relative shifting between the end plate and the stator during the bolting of the end plate to the stator will make practically no change in the "close point."

The construction is also adapted for water cooling of the oil reservoir if such should be found necessary. All that need be done is to remove the cover plate 11 and replace it with one having a water jacket.

Being aware of the possibility of modifications in the particular structure herein described without departing from the fundamental principles

of my invention, I do not intend that its scope be limited except as set forth by the appended claims.

- Having fully described my invention, what I claim as new and desire to secure by Letters Patent of the United States is:
1. In a rotary compressor, a stator member having a rotor receiving opening and with a bore at right angles to the opening, said bore having a fluid inlet at one end and being connected at the other end to the opening to form an inlet port for the latter end plates fixed to the stator, a rotor shaft, a rotor mounted on the shaft and provided with blades, means for driving the rotor, said driving means removably secured to said rotor, means comprising unloading valve mechanism contained in the bore for preventing fluid from passing therethrough to the compressor inlet port when the compressor has caused a predetermined fluid pressure to be developed, and ports communicating with the bore and formed partly in the stator member and partly in the end plate.
  2. In a rotary compressor, a stator member having a rotor receiving opening and with a bore at right angles thereto, said bore having a fluid inlet at one end and being connected at the other end to the opening to form an inlet port of the compressor, end plates fixed to the stator, a rotor shaft, a rotor mounted on the shaft and provided with blades, means for driving the rotor, said driving means and said rotor having interengaging slotted portions to operatively connect same together, a valve contained in the bore in the stator member for preventing flow of fluid from the bore inlet to the compressor inlet port, a spring in said bore for biasing the valve to open position, a fluid motor for closing the valve, and means comprising drilled passages in the stator and end plate for placing the motor in communication with fluid under pressure developed by the compressor.
  3. In a rotary compressor, a stator casting provided with removable ends, a non-rotary shaft carried by one of said ends in eccentric relation to the stator, a rotor having radially movable blades mounted on said shaft, said rotor having end teeth, a shaft bearing removably mounted in the other stator end and provided with end teeth engaging with the end teeth of the rotor, a driving shaft having a non-circular portion engaging with the bearing, a pulley on the driving shaft, and a removable member secured to the second named end for holding the teeth of the bearing in engagement with the teeth of the rotor.
  4. In a rotary compressor, a stator casting provided with removable ends, a non-rotary shaft carried by one of said ends in eccentric relation to the stator, a rotor having radially movable blades mounted on said shaft, said rotor having end teeth, a shaft bearing removably mounted in the other stator end and provided with end teeth engaging with the end teeth of the rotor, a driving shaft having a non-circular portion engaging with the bearing, a pulley on the driving shaft, a sealing ring contacting the outer face of the bearing, removable means for retaining the sealing ring in position, and spring-actuated means carried by the rotor shaft for biasing the bearing against said sealing ring.
  5. In a rotary compressor, a stator casting provided with removable ends, a non-rotary shaft carried by one of said ends in eccentric relation

to the stator, a rotor having radially movable blades mounted on said shaft, an oil reservoir in the end carrying the shaft, a filter chamber in the portion of the shaft located in said end, a tubular filter of less diameter than the chamber positioned therein, an oil passage leading from the interior of the filter to the periphery of the shaft within the rotor, a second oil passage leading from the exterior of the filter to the reservoir, and means for securing the shaft against rotation, said locking means also closing the filter chamber.

6. In a rotary compressor, an integral stator casting having formed therein a circular rotor chamber and a transverse valve bore, said bore communicating adjacent one end with the chamber and adjacent the other with the atmosphere, a primary unloading valve controlling said latter communication, fluid-operated means for closing said primary valve including a removable retaining plate, a removable end plate for the casting carrying a rotor with sliding blades eccentrically mounted in said chamber, and a port for said fluid-operated means, said port being formed partly in the casting, partly in the end plate and partly in the retaining plate.

7. In a rotary compressor, an integral stator casting having formed therein a circular rotor chamber and a transverse valve bore, said bore communicating adjacent one end with the chamber and adjacent the other with the atmosphere, a primary unloading valve controlling said latter communication, fluid-operated means for closing said primary valve including a removable

retaining plate, a removable end plate for the casting carrying a rotor with sliding blades eccentrically mounted in said chamber, an oil separator including a supporting plate removably secured to the end plate, and a port for said fluid-operated means, said port being formed partly in the casting, partly in the end plate, partly in the retaining plate and partly in the supporting plate.

10 8. In a rotary compressor, an integral stator casting having formed therein a circular rotor chamber and a transverse valve bore, said bore communicating adjacent one end with the chamber and adjacent the other with the atmosphere, 15 a removable end plate for the casting carrying a rotor with sliding blades eccentrically mounted in said chamber, a secondary unloading valve mechanism communicating with the bore, a cap for retaining said secondary valve mechanism, and a port for the latter formed partly in the casting, partly in the end plate and partly in the cap.

9. In a rotary compressor, a stator, end plates fixed to the stator, a rotor supporting shaft fixed to one end plate and projecting into the stator with its axis eccentric to the axis of the stator, a rotor including blades rotatably mounted on the shaft, a driving shaft mounted in the other end plate in axial alignment with the rotor shaft, 25 means including interengaging toothed members for connecting the driving shaft to the rotor, and sealing means between the driving shaft and said other end plate.
